UNITED STATES PATENT OFFICE.

HENRY C. TRAUTE, OF MONMOUTH BEACH, NEW JERSEY, ASSIGNOR TO THE DIAMOND MATCH COMPANY, OF CHICAGO, ILLINOIS, A CORPORATION OF ILLINOIS.

SMOKER'S OUTFIT.

Application filed September 18, 1924. Serial No. 738,358.

To all whom it may concern:

Be it known that I, HENRY C. TRAUTE, a citizen of the United States, and resident of Monmouth Beach, in the county of Monmouth and State of New Jersey, have invented certain new and useful Improvements in Smokers' Outfits, of which the following is a specification.

This invention relates to smokers' outfits, and it has for its object to provide a combination ash tray and cigarette and book match stand of such construction that, in addition to its primary function as a convenient and attractive desk or table utensil for a smoker, it affords an efficient means whereby cigarettes and matches can be safely packed in segregated quantities for shipment in a single package.

To this end my invention comprises novel features of construction and combinations of parts which will be hereinafter described and claimed.

In the drawings—

Figure 1 is a perspective view of a smoker's outfit embodying my invention, the lid of the cigarette holder being shown as swung upward and the match and ash tray as partially withdrawn.

Fig. 2 is a longitudinal vertical section of the outfit with match books indicated therein in dotted lines.

Fig. 3 is a fragmentary perspective view of one end of the structure.

Referring to the drawings, 4 designates a case preferably of sheet metal and of appropriate form and size to receive a commercial packet of cigarettes or the contents of such packet. This case comprises a bottom 5, sides 6, ends 7, and a hinged lid or cover 8. On the respective ends 7 are vertically-disposed open-mouth pockets, preferably tapering from top to bottom, as shown, to receive and accommodate the usual commercial book matches with the larger ends of the books projecting well above the top of the case in order to facilitate the ready withdrawal and return or replacement of the books, as occasion may require. Each pocket preferably comprises a piece of sheet metal shaped to provide an outer side wall 9 and two tapering ends 10, which latter are fixedly secured to the adjacent end of the case, as, for example, by interlocking tongues 11 and slots 12 in the contiguous ends of the pocket and case re-

spectively. The end of the case, which is spaced from the outer wall of the pocket, constitutes a part of the inner wall of the latter. The outer side wall and the ends of each pocket are extended below the bottom of the case, as at 13, said wall being provided at its lower end with an inturned portion 14 which constitutes the bottom of the pocket and terminates in an extended angular portion 15 which presents an elongated ledge or flange for the support of one end of a tray 16 that may be positioned beneath the case. The depending extensions of the pocket ends are formed with integral wings 17 which are bent inward below and parallel to the adjacent end of the cigarette case so as to complete the lower portion of the inner wall of the pocket or match holder.

The tray 16 is a rectangular drawer, preferably of sheet metal, which, being slidably seated at its ends upon the respective basal ledges 15 of the book-match pockets or holders, can be readily slid into position beneath or from the bottom of the cigarette case, as desired.

When the tray is positioned beneath the case the bottom of the latter entirely covers and encloses the top of the tray, which tray is preferably of proper dimensions to contain four books of matches placed therein flatwise in superposed pairs, as indicated at *m* in Fig. 2. Hence when the tray is closed the books therein are within a fire-proof container and are separate from the contents of the case, thus permitting the safe packing and transportation of book-matches and cigarettes in a single package. A pack of cigarettes is indicated at *c* in Fig. 2.

It is to be noted that the depending portions of the book match pockets or holders at the respective ends of the structure afford suitable supporting members for the outfit when it is placed upon a table or the like; that books can be readily removed from the tray and properly inserted into the pockets or holders for convenient use; that the cigarettes, if they be confined in a packet, can be withdrawn and loosely deposited in the case for individual removal as desired, and that the tray can be slid beyond either side of the case to serve from time to time as a convenient ash, waste match and cigarette stub receptacle and then can be readily closed to confine the ashes,

&c. Consequently my invention affords a simple, compact and convenient smoker's outfit, the surface of which may be made quite plain or be more or less embellished to meet particular requirements.

It is to be understood that I do not limit my invention to the specific details of construction herein disclosed, as the device may be modified within the principle of the invention and the scope of the appended claims.

I claim—

1. A smoker's outfit comprising a rectangular receptacle for cigarettes, exterior match-holding pockets affixed to the respective ends of said receptacle, and an ash-receiver movably supported beneath said receptacle, said pockets composed of sheet metal shaped to provide outwardly spaced wall portions and tapering ends depending below the body of the receptacle and affording guides and supports for the ash receiver.

2. A smoker's outfit comprising a receptacle for cigarettes, match holding pockets arranged on said receptacle and extending below the latter, the depending portions of the pockets having tray supports, and an ash receiver slidably mounted on said supports and directly beneath the receptacle.

3. A smoker's outfit comprising a receptacle for cigarettes, match holding pockets

on the respective ends of the receptacle, each of said pockets comprising a hollow metal structure secured to and depending below the adjacent end of the receptacle and having a tray support, and a tray slidably mounted on the supports and directly beneath the receptacle.

4. A smoker's outfit comprising a receptacle for cigarettes, match holding pockets on the respective end walls of the receptacle, each of said pockets comprising sheet metal bent to form an outer wall, end walls, and a bottom, said bottom having a depending angular portion constituting a tray support, and a tray slidably mounted on the supports and directly beneath the receptacle.

5. A smoker's outfit comprising a rectangular receptacle for cigarettes, match holding pockets arranged exteriorly of the ends of said receptacle and including depending portions, said ends constituting inner wall portions for the pockets and the depending portions of the pockets having tray supporting members, and a tray slidably supported on said members and in close relation to the bottom of the cigarette receptacle.

Signed at New York in the county and State of New York this 16th day of September, A. D. 1924.

HENRY C. TRAUTE.
